(57) **CLAIM**

The ornamental design of a wiring connector, as shown and described.

DESCRIPTION

FIG. 1 is a front, top and right side perspective view of a wiring connector showing my new design, in an open condition;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a front, top and right side perspective view thereof, in a closed condition;

FIG. 9 is a top plan view thereof;

FIG. 10 is a bottom plan view thereof;

FIG. 11 is a right side elevation view thereof;

FIG. 12 is a left side elevation view thereof;

FIG. 13 is a rear elevation view thereof;

FIG. 14 is a front elevation view thereof; and,

FIG. 15 is a front, top and right side perspective view thereof, in an open condition, and showing with different environment.

The broken line in the figure drawings is included for the purpose of illustrating environment and forms no part of the claimed design.
